UNITED STATES PATENT OFFICE.

CLAYTON E. FREDERICKSON, OF SAN FRANCISCO, AND IVY BALDWIN, OF ALAMEDA, CALIFORNIA, ASSIGNORS OF ONE-HALF TO WILLIAM H. STENGER, OF BERKELEY, CALIFORNIA.

LIFE-SAVING APPARATUS.

1,056,271.

Specification of Letters Patent.

Patented Mar. 18, 1913.

Application filed May 2, 1912. Serial No. 694,622.

To all whom it may concern:

Be it known that we, CLAYTON E. FREDERICKSON and IVY BALDWIN, residing, respectively, in the cities of San Francisco and 5 Alameda, counties of San Francisco and Alameda, and State of California, have invented a new and Improved Life-Saving Apparatus, of which the following is a specification.

10 This invention, which generally is in the nature of an improved life-saving net, is more especially designed for forming a part of fire apparatus for cities, and it has for its object to provide an inexpensive, compact and easily manipulated body catching means, easily mountable upon an auto truck and so arranged, whereby the truck with the catching means can be backed up against a burning building and easily controlled for 15 catching persons who jump from the windows or the top of the said burning building.

Our invention also has for its object to provide a life saving apparatus of the kind 20 generally outlined in which the apparatus can be almost instantly set up for use by cranking the same and the catching means is readily folded up when not in use.

With other objects in view that will be 25 hereinafter apparent, our invention consists in the peculiar arrangement and combination of parts, all of which will be herein-after explained, specifically pointed out in the appended claims, and illustrated in the 30 accompanying drawings, in which:

Figure 1, is a perspective view of our invention, the same being shown as adjusted for use. Figs. 2 and 3, represent a side elevation of the complete apparatus, the parts 35 being in the folded or traveling position. Fig. 4, is a transverse section thereof, the parts being adjusted for catching the jumper, as in Fig. 1. Fig. 5, is a similar view, the parts being in their folded or 40 closed position. Fig. 6, is a detail section of the worm drive for opening and closing the net or apron carrying pivoted side arms. Fig. 7, is a detail view that shows the manner of connecting the crank shaft with the 45 worm carrying shaft. Fig. 8, is a detail view hereinafter referred to.

In carrying out our invention, and in the preferred form thereof, we employ an auto truck 1 of any approved type, and which 50 includes the longitudinal angle bars 2-2,

upright brackets 3 and upon each opposite pair of which, (three opposite pairs being shown) is mounted a transverse I bar 4 that forms the bed or support for the catching means, the peculiar construction of the co-operative parts of which, form the essentials of our invention. The cross bars 4, extend laterally of the truck and on the outer ends of each of the said bars 4 is mounted a bearing box 5, those at each side alining to accommodate the rock shafts 6. A series of side bars 7 are fixedly connected to each rock shaft 6 to rock therewith, the upper ends of which curve upwardly, as at 70, whereby, when the parts are folded or 60 closed, as in Fig. 5, for traveling to and from the place of fire, the several parts will be compactly closed or folded up over the top of the truck.

8 designates a main shaft that extends longitudinally of and is disposed midway of the truck, the said shaft being journaled in short upright brackets 80 mounted on the cross bars 4, as is best shown in Figs. 4 and 5. 75

9 designates double grooved guide pulleys, one of which is provided for each opposing pair of side bars 7 and the said pulleys are keyed upon the central or main shaft 8. 80

10 and 20 designate cable connections for the opposite side bars 7, one of which 10, connects with the upper ends of the arms 7 at one side passes around one part of one of the corresponding double pulleys and passes 90 to and connects with the lower end of the said side arm 7, the other cable 20 likewise connecting the other side bar 7.

12 designates a worm on the shaft 8 that meshes with a gear 9 on a transverse shaft 95 95 journaled in upright brackets 91 that extend up from one of the end cross frames.

Shaft 9 at one end has a lateral stud 92 for co-operating with the socket 93 that forms part of a crank shaft 94 and which 100 has a bayonet slot 95 for engaging the stud 92.

75 designates a flexible body which may be a netting or an apron, which extends the full length of the side rods 76 that connect the upper ends of the arms 7. The opposite sides of the net or apron 75 are fixedly connected to the said rods 76 and in such a manner so that when the arms 7 are swung out to the position shown in Figs. 1 and 4, a 110

yielding net or apron is provided for catching the jumper, it being understood that since the opposite ends of the arms 7 are joined with the central or main shaft by the flexible members that wind one or more about their respective drums on the main shaft, said flexible connections will tend to creep on the drums or pulleys when under excess strain and thereby materially over-
come tendency of the ends of the net tearing from the side rods to which they are connected. If desired the side edges of the apron or net may be provided with yielding portions in the nature of springs 78, as shown in Fig. 8. When the arms 7 are swung inwardly, by cranking the main shaft, the apron or net will double and hang folded, as shown in Fig. 5.

From the foregoing taken in connection with the accompanying drawings, the complete construction, the manner of its operation and the advantages of our invention will be readily apparent.

While the general arrangement of the parts as shown and described discloses a preferred form of our invention, yet we do not limit ourselves to the exact details or combination of parts shown, since they may be readily modified or varied and come within the scope of the appended claims.

What we claim is:

1. A portable body catching apparatus, comprising a truck having a bed frame, arms rockably mounted at each side of the bed frame, a crank shaft, devices connecting said shaft to said arms at each side of their fulerums for swinging the said side arms inwardly and outwardly in a plane at right angles to the frame, and a flexible body connected at the opposite edges to the side arms and adapted when the side arms are

swung out to form a net or apron for receiving a falling body thereon.

2. In a life saving apparatus of the character described; a bed frame, a flexible and foldable body, means for drawing out the said body to form a catching net or apron, said last named means including pivotally rockable side arms and crank actuated means on the bed frame for adjusting the first said means to draw out or fold up the said net or apron, said crank actuated means comprising a centrally longitudinally located crank shaft, and power transmitting cable connections encircling said crank shaft and having their ends secured to the rockable side arms, one end at one side of the pivot and the other end at the other side of the pivot of the respective arms.

3. In a life saving apparatus of the character described; a bed frame, said frame including cross bars, a rock shaft for each side of the apparatus journaled in bearings on the ends of the cross bars, vertically swingable side arms mounted on each of the rock shafts to rock therewith, a longitudinal shaft mounted on the bed frame midway of the rock shafts and having winding drums, flexible connections wound on the drums, one end of each of the said connections joining with the upper end of its respective side arm, and the other end of the said connections joining with the lower end of the said side arm, means for reversely rotating the drum shaft and a flexible apron or net whose opposite ends join with the upper ends of the side arms.

CLAYTON E. FREDERICKSON.

IVY BALDWIN.
